UNITED STATES PATENT OFFICE.

JAMES T. ANDREW, OF MONTGOMERY, ALABAMA.

SAFETY APPLIANCE FOR RAILROAD-CARS.

No. 864,058.

Specification of Letters Patent.

Patented Aug. 20, 1907.

Application filed December 27, 1906. Serial No. 349,727.

To all whom it may concern:

Be it known that I, JAMES T. ANDREW, a citizen of the United States, residing at Montgomery, in the county of Montgomery and State of Alabama, have 5 invented certain new and useful Improvements in Safety Appliances for Railroad-Cars; and I do hereby declare the following to be a full, clear, and exact description of the invention, such as will enable others skilled in the art to which it appertains to make and 10 use the same.

My invention relates to improvements in safety appliances for railroad cars, and the object of my invention is to provide means whereby derailment of a train, with the injurious effects resulting therefrom, shall be 15 rendered practically impossible, this application being in the nature of an improvement upon my former application, Serial No. 317,578, filed May 18, 1906.

My invention is applicable not only to railroad cars, but also to electric cars of all descriptions, and to locomotives.

With this object in view, my invention consists in the construction and combinations of parts as herein-after described and claimed.

In the accompanying drawing, Figure 1 represents 25 a side view of a railway truck showing my invention applied thereto, and a portion of the track. Fig. 2 is an end view of the same with the plow removed. Fig. 3 is a side view partly in section of a portion of my device on an enlarged scale with the plow omitted, 30 Fig. 4 is a view similar to Fig. 3 showing the position assumed when a derailment of the car wheels occurs.

In Fig. 1 of the drawings is represented the truck of an ordinary passenger car with my improvements applied thereto.

35 *a* represents the truck side frame, *b* the pedestal tie bar, *c* the equalizer, *d* the equalizer springs, *e* the spring band, *f* the pedestal, *g* the axle box, and *h* the axle carrying the wheels *i*, these parts being of the usual, or any preferred, construction. Between the 40 equalizer and the pedestal tie bar are mounted springs *j* to produce a cushioning effect or destroy the shock when the guide rollers, hereinafter referred to, come into play. These guide rollers *k*, which take the place of the sliding shoes, shown in my prior application, 45 above referred to, are mounted in the extension frame *m* bolted to the pedestals. There are two of these rollers for every car wheel, one on the inside and one on the outside thereof, or eight rollers for every ordinary four-wheeled truck. As shown in Fig. 2, these 50 rollers each have a ridge *n*, and this ridge is always located on the inside part of the roller. These rollers *k* are mounted on axles *o*, which slide freely in slots *p* in the extensions *m* fastened to the pedestal. These 55 slots are inclined from the center downwardly in each direction, as shown in Fig. 1. These rollers are normally held at the top of this inverted V slot *p*, by

means of springs *q*, one located on each side of each roller, said springs terminating in meniscus shaped blocks *r*, the inner surfaces of which are adapted to bear against the rollers *k*, thereby forming brake blocks. 60 The outer ends of each of the springs *q* are seated in slots *z* in the frame *m*. To prevent the brake shoes *r* from becoming disengaged from the rollers *k*, in the event of a derailment, in which case the rollers would assume the position shown in Fig. 4, I provide additional supporting springs *3* connected to the frame *m* and to the upper part of each brake block *r* respectively. These springs are weaker than the springs *q*, and the brake blocks *r* are held up against the rollers *k* and held against said rollers under all conditions by 70 means of the springs *q* and *3*. To prevent rattling each of the slots *p* at its upper highest point is preferably provided with a slight depression *s*, in which the axle *o* of the corresponding roller rests, the construction being the same on each side of the roller. Under ordinary conditions, therefore, the rollers will keep the 75 position shown in Figs. 1 and 3.

To the main frame of the truck are attached depending beams *t* and *u* in which the inner rollers of each set are journaled, and to this frame is also attached a depending center beam *v*, to which is attached an approximately triangular brace *w*, passing through which, and attached to the beams *t* and *u*, is a casing *x*, which surrounds the axle *h*, but does not contact therewith or form a bearing therefor, this casing being provided to 85 prevent injury to the truck in case of a broken axle. Snow plows *y* are preferably attached, one at each end of said truck, to prevent the snow from reaching the rollers *k* and displacing them.

The operation is as follows. In case the train leaves 90 the track for any reason, as, for example, if the track is spread, and especially while traveling around a curve, some part of the truck will drop slightly, and one or more of the eight rollers *k* will strike the rail. The result will be that this roller will be displaced from its 95 highest position, as shown in Fig. 3, and thrown down so that its axle rests in the lowest portion of the slots *p*, as shown in Fig. 4, for example, compressing the corresponding springs *q*. The compression of the springs *q* causes the meniscus shaped part *r* to press against the 100 roller, thus acting as a brake and gradually converting the roller into a sliding shoe. The downward movement of the roller, or rollers, in the slots *p*, will, at the same time, lift the truck and cause the car wheels to be lifted over any obstacles, such as frogs or switches. 105

The train sliding along the track will soon be brought to a stand still, but preferably an arrangement is used whereby the forcible displacement of the rollers from the position shown in Fig. 3 to that shown in Fig. 4, will automatically set the air brakes, such connections 110 being illustrated in Figs. 6 and 7 of my application, above referred to, it being deemed unnecessary to re-

produce these figures in the present application. In fact the general invention is similar to that shown in my application above referred to, except that in place of swinging shoes, rollers are employed.

5 Having thus described my invention, what I claim as new and desire to secure by Letters Patent, is:

1. In a safety appliance for cars and locomotives, the combination of trucks and means carried thereby for automatically lifting said trucks and applying a braking action in case of accident, said means including spring supported rollers, and frames provided with slots in which the axes of said rollers are mounted, said frames being carried on the truck frame, substantially as described.
- 15 2. In a safety appliance for cars and locomotives, the combination of trucks and means carried thereby for automatically lifting said trucks and setting the brakes in case of accident, with snow plows mounted on said trucks, substantially as described.
- 20 3. In a safety appliance for cars and locomotives, the combination of trucks having depending side beams and pedestals, slotted frames attached thereto, a roller carried in each of said frames, springs supporting said roller, brake shoes held against said rollers by said springs, and 25 a casing including the car axle, the whole structure being braced together, substantially as described.
- 30 4. In a safety appliance for cars and locomotives, the combination of trucks, frames carried thereby provided with slots of inverted V-shape, rollers whose axes are 35 mounted in said slots, springs for normally holding said rollers at the highest point of said slots, said rollers being provided with flanges corresponding to the gage of the rails, substantially as described.
- 40 5. In a safety appliance for cars and locomotives, the combination of trucks, slotted frames carried by said trucks, each of said slots being in the shape of an inverted V, rollers whose axes are mounted in said slots, each of said rollers being provided with a flange, and the flanges on the pairs of rollers corresponding to the gage 45 of the rails, a brake shoe, one on each side of said rollers, and springs bearing against said brake shoes, and normally holding the axes of the rollers at the highest points of the slots, substantially as described.
- 50 6. In a safety appliance for cars and locomotives, the combination of a truck and a plurality of paired rollers, one pair for each wheel, the outer and inner rollers of
- 55 each corresponding pair being of the same gage as the railroad, slotted frames carried by the car track in which the axles of said rollers are mounted, and tension springs normally holding the axles of said rollers at the highest point of said slots while allowing said axles to slide down in either direction to the lower ends of the slots in case of accident, thereby lifting the car wheels above the level of the rails, substantially as described.
- 60 7. In a safety appliance for cars and locomotives, the combination with a truck, of a pair of rollers for each wheel, slotted frames carried by said truck, in which slots the axles of the rollers are mounted, said slots being shaped like an inverted V, and said rollers being each provided with a flange, the flanges on corresponding rollers corresponding to the gage of the railroad, a brake block bearing on each side of each of said rollers, a spring connected to each brake block and the supporting frame, whereby the axes of the rollers will be normally held at the highest point of said slots, and a snow plow located at 65 each end of said truck, substantially as described.
- 70 8. In a safety appliance for cars and locomotives, the combination of trucks, supporting frames carried thereby, each frame being provided with slots made like an inverted V but having a cut away portion at the highest point on its lower side, flanged rollers whose axes are located in said slots, two brake shoes bearing on each roller, one at each side thereof, and springs, one end of each of which bears against one of the brake shoes and the other end against the slotted frame, substantially as described.
- 75 9. In a safety appliance for cars and locomotives, the combination with a truck frame including the equalizers, and pedestals, springs between the equalizers and pedestals, slotted frames carried by said pedestals, and beams depending from said truck, and a plurality of rollers, two for each car wheel, one mounted inside of said car wheel, and the other outside of the same, the axles of said rollers being carried in the slots in said frames, two brake shoes for each roller, one located on each side thereof, and a spring connected to each brake shoe and bearing in a socket in said slotted frame, substantially as described.

In testimony whereof, I affix my signature, in presence of two witnesses.

JAMES T. ANDREW.
